CLAIM

The ornamental design for a lid for welding electrode storage, as shown and described.

DESCRIPTION

FIG. 1 is a front elevation view of a design of a lid for welding electrode storage. The right side elevation view, the left side elevation view, and the rear elevation view are identical thereto.

FIG. 2 is a bottom plan view of the lid;

FIG. 3 is a top plan view of the lid; and,

FIG. 4 is an isometric view, at a smaller scale, showing the front, top, and right side.

The broken lines in the drawings illustrate environmental structure or boundaries that form no part of the design to be patented.
